UNITED STATES PATENT OFFICE

2,185,492

ORNAMENTAL OBJECT

Robert N. Barrett, Houston, Tex.

Application December 13, 1937, Serial No. 179,455

9 Claims. (Cl. 41—30)

This invention relates to an ornamental object and to a process for making the same.

It is an object of this invention to produce a sign, decorative pattern, ornamental block or 5 the like having inlaid portions of different colors, some of which may be transparent, and to provide a process whereby the colored portions may be made of any shape desired, and the various colors arranged in any manner desired.

10 Another object is to provide a method of making such a multi-color object without using extreme care in order to avoid mixing or intermixing of the colors so used.

Another object is to produce an ornamental 15 member in which the main features of the design or ornament are molded, cast, stamped or otherwise formed from any plastic malleable material, or other material to form in one rigid piece a matrix strong enough to support itself 20 and which has depressions or recesses into which the various colored materials are filled or laid.

Other objects of the invention will become apparent as the description of the invention proceeds.

25 A representative form of the invention is illustrated in the accompanying drawing, in which:

Fig. 1 illustrates one side of the matrix before filling;

Fig. 2 is a vertical sectional view on the line 30 2—2 of Fig. 1 showing the matrix after the side appearing in Fig. 1 has been filled with a colored material;

Fig. 3 illustrates the opposite face of the matrix shown in Fig. 1 before the depressions therein 35 have been filled;

Fig. 4 is a vertical sectional view along the line 4—4 of Fig. 3 after the depressions in the face appearing in Fig. 3 have been filled with a colored material;

40 Fig. 5 is a vertical sectional view taken on the line 2—2 of Fig. 1 after the matrix has been filled in from opposite surfaces, being a combination of Figs. 2 and 4;

Fig. 6 shows the matrix of Fig. 5 in which one 45 of the surfaces has been ground off to expose all colors to that surface;

Fig. 7 is a vertical sectional view of Fig. 6;

Fig. 8 shows the matrix of Fig. 5 in which both 50 surfaces have been ground off to expose all colors so that they are visible from both sides; and,

Fig. 9 is a vertical sectional view of Fig. 8.

In accordance with this invention, a shell or matrix 1 is formed of some plastic material, malleable material or composition capable of supporting itself. The matrix may be formed of

colored material and may be transparent if desired. It is formed by any of the die-forming processes well known in the art or it may be cast, molded or carved.

Viewing Figs. 1 and 2, the cavities or recesses 5 2 are formed in the process of making the matrix. These recesses correspond to the shape and extent which one of the contrasting colored materials is to assume. In Figs. 1 and 2, the recesses take the form shown in Fig. 6 where the 10 recess is hatched for the color red. The recesses are then filled with the colored material 3, which, as shown in Fig. 6, is red.

Then the matrix is turned over to the position shown in Figs. 3 and 4, so that it rests on 15 the surface 4. For illustration only, it is assumed that a sign depicting the letter B is being formed. The matrix in the position of Fig. 3 shows the letter B which letter of course has the same color as the material of the matrix. The 20 recesses 6 are now filled in with a third contrasting color 7, blue, for example, as shown by the color hatching in Fig. 6.

The recesses 2 and 6, it is to be noted, do not 25 extend from one surface 4 to the other surface 5, but they are of sufficient depth to retain a considerable amount of the colored materials. The bottoms of the recesses terminate short of the surfaces 4 and 5, leaving a surface having some thickness. In other words, the recesses 30 extend substantially to the opposite surfaces of the matrix.

The recesses are filled in with the colored 35 materials, usually by pouring the material in molten or plastic condition. The material is allowed to harden and grip the walls of the recesses in the matrix.

The matrix is brought back to the position shown in Fig. 5 and is ready for the operation 40 wherein the surface 4 is to be removed. Referring more particularly to Figs. 6 and 7, the surface 4 has been removed by grinding or some similar operation, so as to expose all three colors to that surface, that is, the color of the matrix, the red color of recesses 2 and the blue color of 45 recesses 6.

Referring to Figs. 8 and 9, the surface 5 has 50 been removed by grinding or some similar operation, so that all three colors are visible from both sides.

The function of the matrix is to provide a form for the filled-in colored materials and to serve as the principal element of the decoration or design.

When both the surfaces are ground off to

expose the filled-in materials, the matrix and the filled-in materials form an integral or solid structure wherein each and every color is of the same thickness from top to bottom. When the 5 matrix or any of the filled-in colored materials are of transparent or translucent materials, it is obvious that light can penetrate therethrough, thus affording an object capable of a lighted or illuminated effect when some form of illumination 10 is employed.

The shell or matrix need not form an outer or external encompassing frame for the entire structure. Also, the colored materials can be molded or cast separately to the shape of the 15 recesses and then dropped into said recesses and secured to the walls thereof.

By employing the process herein disclosed, it is evident that each contrasting colored material need not be carefully placed in its respective 20 recess to avoid overflow and mixing with adjacent colored materials, as is necessary in making ornamented objects of a similar nature in the prior art.

Instead of first making the shell or matrix as 25 hereinbefore described, it is also contemplated by this invention that the inserted portions of the composite member may be molded or pressed into the desired shape and then placed together with the material, which is eventually to form 30 the supporting and combining member, in liquid or plastic form therebetween. In this instance the molded inserted portions in effect form a mold for shaping the part which is later to act as a frame and supporting member instead of the frame forming the mold for the colors as in the previously discussed form. It is 35 also within the purview of this invention to mold such color parts by passing them between rotating cylindrical dies and to bring them into proper 40 relation to each other by passing them between other rotating rollers, placing the supporting portion between them when they are in this proper relation. By this means a continuous process may be evolved and the process of making the 45 articles contemplated by this invention greatly accelerated.

In the annexed claims, I desire to claim all modifications of my invention which fall within the purview of its generic spirit.

50 Having described my invention, I claim:

1. The process of making a multi-color molded ornamental object which comprises employing a colored matrix of substantial thickness having parallel oppositely disposed working surfaces, 55 each of said surfaces being divided into recesses, the recesses of any one surface not extending through the other surface, filling the recesses on one surface with a material of one color, filling the recesses on the other surface with a material of another color and then effacing one of said surfaces to permit the colored material filled into the recesses of the other surface to be visible at said effaced surface.

60 2. The process of making a multi-color molded ornamental object which comprises employing a colored matrix of substantial thickness having parallel oppositely disposed working surfaces, each of said surfaces being divided into recesses, 65 the recesses of any one surface not extending through the other surface, filling the recesses on one surface with a material of one color, filling the recesses on the other surface with a material of another color and then effacing both of said 70 surfaces to permit the colored materials filled

into all of the recesses to be visible at said effaced surfaces.

3. The process of making a multi-color molded ornamental object which comprises employing a colored transparent or translucent matrix of substantial thickness having parallel oppositely disposed working surfaces, each of said surfaces being divided into recesses, the recesses of any one surface not extending through the other surface, filling the recesses on one surface with a material of one color and then filling the recesses on the other surface with a material of another color. 10

4. The process of making a multi-color molded ornamental object in which mixing of said colors 15 is avoided and which comprises employing a colored matrix of substantial thickness having parallel oppositely disposed working surfaces, each of said surfaces being divided into recesses, the recesses of any one surface not extending through the other surface, filling the recesses on one surface with a material of one color, filling the recesses on the other surface with a material of another color, and then effacing one of said surfaces to permit the colored material filled into 20 the recesses of the other surface to be visible at 25 said effaced surface.

5. The process of making a multi-color inlaid object comprising forming in the opposite faces of a matrix depressions each extending more 30 than half of the thickness of the matrix, but less than the entire thickness thereof, and having outlines corresponding to the outlines desired for those of the colors in the finished product, respectively, filling said depressions from the opposite faces of said matrix with different desired 35 colors, and effacing one surface of the composite member so produced to expose the color filled in from the opposite surface thereof.

6. The process of making a multi-color ornamental object comprising forming into the desired configuration colored bodies of two of the colors which are to make up said object, placing said bodies in the complementary overlapping relation with respect to each other which they are to occupy in the finished product, and with one face of each of said bodies projecting beyond the corresponding face of the other body, and molding between said bodies a third body adapted to unite and support in predetermined relation with 45 respect to each other said first two bodies.

7. The process of making a multi-color ornamental object comprising forming into the desired configuration colored bodies of two of the colors which are to make up said object, placing 55 said bodies in the complementary overlapping relation with respect to each other which they are to occupy in the finished product, and with one face of each of said bodies projecting beyond the corresponding face of the other body, and molding between said bodies a third body of a different one of the colors which are to make up said object and adapted to unite and support in predetermined relation with respect to each other said first two bodies.

8. The process of making a multi-color inlaid object comprising forming in the opposite faces of a matrix depressions each extending more than half of the thickness of the matrix, but less than the entire thickness thereof, and having outlines 70 corresponding to the outlines desired for colored portions in the finished product, filling said depressions on the opposite faces of said matrix with desired colored material, and effacing one surface of the composite member so produced to 75

expose the color filled in from the opposite surface thereof.

9. The process of making a multi-color ornamental object comprising forming into the desired configuration colored bodies which are to form parts of said object, placing said bodies in the complemental overlapping relation with respect to each other which they are to occupy in
- the finished product, and with one face of each of said bodies projecting beyond the corresponding face of the other body, and molding between said bodies a third body adapted to unite and support in predetermined relation with respect to each other said first two bodies. 5

ROBERT N. BARRETT.
